178,692

BUILDING

Lee Paxton, Jr., and Phillips McCaslin, Greeneville, Tenn.

Application October 6, 1955, Serial No. 38,251

Term of patent 14 years

(Cl. D13—1)

Figure 1 is a front perspective view of a building showing our new design; and

Figure 2 is a rear perspective view thereof.

The opposite side of the building, not shown, is substantially like the side shown.

The suspended awning valance shown fragmentarily in full lines extends entirely around the upper edges of the building as indicated by the broken lines. The awning is lined to indicate color contrast.

We claim:

The ornamental design for a building, substantially as shown and described.
